(57) **CLAIM**

The ornamental design for a wheelchair ramp, as shown and described.

DESCRIPTION

FIG. 1 is a front elevation view of a wheelchair ramp showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged portion taken from line 9-9 in FIG. 7;

FIG. 10 is an enlarged portion taken from line 10-10 in FIG. 7;

FIG. 11 is an enlarged portion taken from line 11-11 in FIG. 8; and,

FIG. 12 is an enlarged portion taken from line 12-12 in FIG. 8.

The dash-dot lines in FIGS. 7, 8, 9, 10, 11, and 12 illustrate the boundaries of the enlarged view indicators and form no part of the claimed design.
